The ornamental design for a tympanic temperature thermometer, as shown and described.

DESCRIPTION

FIG. 1 is a front, right side perspective view of a tympanic temperature thermometer showing my new design;

FIG. 2 is a left side elevational view thereof;

FIG. 3 is a front elevational view thereof;

FIG. 4 is a top plan view thereof;

FIG. 5 is a bottom plan view thereof;

FIG. 6 is a rear elevational view thereof;

FIG. 7 is a left side elevational view of the tympanic temperature thermometer of FIGS. 1-6 with the probe protector pivoted into the closed position;

FIG. 8 is a front elevational view thereof;

FIG. 9 is a top plan view thereof;

FIG. 10 is a bottom plan view thereof; and,

FIG. 11 is a rear elevational view thereof.

FIG. 4.

FIG. 6.

FIG. 5.

Fig. 8.

Fig. 11.

Fig. 1.

Fig. 9.

Fig. 10.
